UNITED STATES PATENT OFFICE.

JOHN B. CLERMONT, OF NEW YORK, N. Y., ASSIGNOR TO S AND S WINDOW CORPORATION, OF NEW YORK, N. Y., A CORPORATION OF NEW YORK.

ATTACHMENT FOR WINDOWS AND THE LIKE.

1,150,174.

Specification of Letters Patent. Patented Aug. 17, 1915.

Application filed September 30, 1914. Serial No. 864,230.

To all whom it may concern:

Be it known that I, JOHN B. CLERMONT, a citizen of the United States, and resident of the borough and county of the Bronx, city 5 and State of New York, have invented certain new and useful Improvements in Attachments for Windows and the like, of which the following is a specification.

My invention relates to windows in which 10 the sashes are capable of a pivotal movement and to other elements which are hinged or pivoted and has for its object to provide an attachment which may be positioned to automatically cooperate with a relatively fixed 15 element for the purpose of arresting the pivotal movement of the sash or the like at predetermined points and which may be brought to an inoperative position when a free and unrestricted pivotal movement of the sash or 20 the like is desired.

My improvement also contemplates constructing the attachment in such a manner that the same can be moved to and from its 25 automatically operative position preferably only by authorized persons thus protecting the same against tampering and undesired manipulation.

Other objects of my invention will appear from the description hereinafter and the features of novelty will be pointed out in the 30 appended claims.

Reference is to be had to the accompanying drawings which by way of example illustrate my attachment as applied to a window 35 having sliding sashes capable of swinging on horizontal pivots under certain conditions.

In the said drawings Figure 1 is a front elevation of a window including my attachment with parts in section; Fig. 2 is a section thereof on the line 2—2 of Fig. 1; Fig. 3 is a similar view showing the sash swung on its pivots relatively to the casing; Fig. 4 is an enlarged detail sectional view of one 45 of the reciprocating stays forming part of the attachment; Fig. 5 is a section thereof on the line 5—5 of Fig. 4; Figs. 6 and 7 are face and edge views respectively of one of the cam plates adapted to cooperate with the stays; and Fig. 8 is a detail view of one form 50 of device or key for moving the reciprocating stay to and from an operative position; Fig. 9 is a face view of said key in use as a chain clamping device; Fig. 10 is a sectional front elevation of a window showing said

key used in this manner and Fig. 11 is a sectional view on the line 11 of Fig. 10.

As shown in the illustrated example the sashes 10 are pivotally connected at 11 for instance with blocks 12 secured to one end of the sash chains or cords 13 and vertically 60 slidable in the customary grooves 14 located in the casing 15 so that said sashes in addition to their vertical sliding movements are capable of a pivotal movement in vertical planes or in other words on the horizontal 65 pivots 11 under certain conditions. In the example shown the chains 13 of each sash pass over pulleys 13^a in pairs to one side of the casing 15 and have their free ends suitably secured to a single sash weight 13^b or 70 to other counterbalancing means. With this arrangement the chains of one sash both pass to the right and the chains of the other sash pass to the left and each sash is balanced by a single weight or by other suitable counter- 75 balancing means. In the drawing only the chains and weight of the lower sash are illustrated for the sake of clearness. The said sashes are normally maintained in their vertical paths in any suitable manner, the illustration showing locking strips 16 for normally locking the lower sash against pivotal movement when in its lowered position while a similar movement of the upper sash in its 80 raised position is prevented by parting strips 85 17, the said locking strips 16 being movable to an inoperative position to permit a pivotal movement of the lower sash when desired.

I will describe my attachment as combined 90 with the lower sash only for the purpose of simplicity of description it being understood that the attachment may be readily combined with the upper sash or with other more or less similarly movable elements if this 95 should be desired.

My improved attachment as shown in the drawings comprises a steel or other metallic case 18 forming part of or secured to a plate 19 provided with an aperture 20. A bridge 100 pin 21 is secured to the inside wall of the case 18 and projects therefrom into the bore of a tubular sleeve 22 which in turn extends exteriorly of the case 18 through the aperture 20 and is provided with spaced annular 105 flanges 23. The bridge pin 21 has a sliding fit with the bore of the sleeve 22 while the outer diameter of the latter is such as to

similarly fit the aperture 20 so that said sleeve 22 is properly supported, by the pin 21 and aperture 20 and the said pin 21 is itself maintained against transverse displacement by said sleeve. With this construction the sleeve 22 is rotatably mounted in the case 18 and is slideable out of the case 18 and lengthwise of the bridge pin 21, the one annular flange 23 serving to limit the said sliding movement of said sleeve 22 for the purpose to be more fully described hereinafter. A resilient stay arm 24 preferably of spring steel or other suitable material is rigidly secured to the sleeve 22 exteriorly of the case 18 and at its free end carries a button head 25 of steel or the like and connected with the arm 24 by means of a shank 26 as clearly shown in Fig. 4. A steel collar 27 surrounds the sleeve 22 between the flanges 23 and has its free ends connected by means of a pin or the like 28 adapted to fit into the forked or notched end 29 of a cam 30 rotatably mounted in the case 18 on trunnions 31, the common axis of the latter extending transversely to the axis of the sleeve 22. The cam 30 is formed at opposite corners with recesses or notches 32 adapted to receive the nose or projection 33 of a counter-acting spring 34 the free ends of which are set in opposite corners of the case 18 as illustrated in Fig. 4. The attachment further includes a cam plate 35 of steel or the like provided with a slot 36 open at one end and preferably provided with a vertical face 37 to form a wide mouth at said open end as shown in Fig. 6. The said slot 36 comprises a portion 38 arranged at an angle to the vertical path in which the sash travels and inclined downwardly from said open end. The portion 38 communicates with a continuing vertical portion 39 the latter in turn being connected with a continuing inclined portion 40 terminating in a seat or closed lower end 41. A resilient tongue or clip 42 preferably stamped from the plate 35 extends outwardly from and in registry with the lower end portion of said slot 36 as clearly shown in Figs. 6 and 7 and forms a pocket 43 as clearly shown in Fig. 7.

In utilizing the attachment in connection with a window the plate 35 is rigidly secured at the proper point to an inside vertical surface of the window casing 15 by means of screws or the like with the open end of the slot 36 projecting upwardly and toward the groove 14 in said casing. The case 18 on the other hand is set into a recess 39 formed in the adjacent vertical side edge of the sash 10 and the plate 19 is secured thereto by means of screws or other fastening devices adapted to extend through apertures 45 whereby the case, stay arm and connected parts are fastened to the sash so as to be movable therewith. With this arrangement it will be seen that the cam-plate 35 is

stationary or fixed relatively to the stay arm 24 and its connected parts. The sash is further provided with a depression 46 extending upwardly from the recess 39 in the said side edge for the accommodation of the stay arm 24, said recess and depression being so proportioned as to depth that no part of said stay arm 24 projects beyond the side edge of said sash in the retracted or inoperative position of these parts of the attachment. In this condition of the parts the button-head 25 and its shank 26 will move in a plane or path to one side of or out of registry with the plane in which the plate 35 is fixed on the casing 15 so that the sash 10 may be freely swung on its pivots 11 when the locking strips 16 are moved to an inoperative position.

To secure the desired automatic co-operation between the elements of my attachment carried by the sash 10 and the part thereof located on the casing 15 it is necessary to move the stay arm 24 in a direction away from the case 18 in order to bring the button-head 25 and its shank into a position where they will automatically co-operate with the plate 35 and its slot 36 at the proper time to arrest a movement of the sash 10 on its pivots 11. In order that this may be accomplished any suitable means may be provided; for instance I may provide the cam 30 with an angular axial opening or recess 47 located in registry with a similar opening in the case 18 and adapted to receive the angular end 48 of a key 49 having an operating handle 50 preferably terminating in a forked projection 51 extending at an angle thereto. This angular end 48 is adapted to be inserted into the angular opening or recess 47 after which the key 49 is rotated in the proper direction by means of the handle 45 to bring about an oscillation of the cam 30 on its trunnions 31. In this manner the forked or notched end 29 of said cam may be moved toward the right in Fig. 4 and owing to its connection with the pin 28 and collar 27 will slide or move the sleeve 22 along the bridge pin 21 also toward the right in said Fig. 4, the nose or projection 33 of the spring 34 being forced out of the one notch 32 of the cam 30 and finally snapping into the other notch 32 to secure said cam and its connected parts in the adjusted position. In its movement along the bridge pin 21 as described the sleeve 22 carries with it the stay arm 24 and thus moves the latter away from the window sash 15 and into the groove 14 of the window casing 15 so that the shank 26 of the button-head 25 is now in the same plane with the slot 36 of the plate 35 or in other words said slot is in the path of said shank. If the sash 15 is now swung on its pivots 11 out of the casing, the strips 16 having been previously opened to permit this, the said shank 26 will at the

proper time enter the slot 36 and travel lengthwise thereof into the seat 41 while the button-head 25 will move below the tongue or clip 42 and press the same against its tension and will finally reach the pocket 43 so that said head 35 will be firmly held and engaged by said clip and accidental movement of the head and shank in a reverse direction out of the slot will be prevented. As the 10 said shank 26 and head 25 thus move into the slot and become seated therein the free end of the stay arm 24 will be held and said arm will describe a pivotal movement on the pin 21 relatively to the case 18 and sash 10 as 15 the latter is pivotally swung and will thus arrest said pivotal movement of said sash and firmly hold it in an inclined position relatively to the window casing 15. In this position of the parts a space exists between 20 the upper and lower sashes through which air enters and passes out thus securing perfect ventilation without any direct drafts. The attachment also permits the lower edge of the sash to be raised to produce a space 25 between said lower edge and the window sill whereby double ventilation may be secured if desired. At the same time the attachment also prevents the accidental complete discharge or free pivotal movement of the sash 30 in case the locking strips 16 should be accidentally left in their open or inoperative positions.

To return the sash to its normal upright position in the casing it is only necessary to 35 bring the sash to its lowermost position and then exert a sufficient pressure thereon toward said casing to overcome the tension exerted by the clip 42 on the head 25 and thus cause the shank 26 to move lengthwise of the slot 36. With the shank 26 in the seat 41 of the slot 36 and the sash swung out of the casing and in its lowermost position therein the arm 24 extends downwardly at a more or less acute angle to the inclined walls of 45 the portion 40 so that the shank 26 is readily moved along the same and lengthwise of the slot toward its open end as pressure is exerted on the sash toward the casing as described. This operation will finally move 50 the shank 26 out of the slot 36 and cause the head 25 to contact with a wall of the groove 14 along which said head 25 will travel as the pivotal movement of the sash 10 in the reverse direction is continued and thus cause 55 the arm 24 to return to its normal upright position. With the lower end of the sash slightly raised from the sill in the outwardly swung position of said sash, the arm 24 will extend perpendicular to the walls of the portion 40 or upwardly at a more or less obtuse angle thereto. If pressure as above described is exerted to swing the sash into the casing when in this raised position the shank 26 will be forced against the walls of said portion 40 and a further inward movement 60

of said sash thus arrested or said shank 26 will be forced more firmly into the seat 41 with the same result. This arrangement thus absolutely prevents the sash from being 70 swung into the casing when in anything other than the proper co-operative position therewith and prevents the one sash from smashing into and damaging the other. In other words the device is rendered absolutely 75 fool proof and proper co-operation is absolutely assured.

The parts are so positioned on the window casing and window sash respectively that a co-operative engagement of one with the other is assured each time the sash is 80 pivotally moved and providing the stay arm 24 is in its outward position so that an absolutely automatic action is absolutely guaranteed. When a complete or free pivotal movement of the sash 10 is desired the 85 end 48 of the key 49 is simply inserted into the aperture 47 and the handle 50 is properly actuated to operate the cam 30 in a direction to slide the sleeve 22 toward the left in Fig. 4, this operation forcing the 90 nose 33 of the spring 34 out of the right hand notch 32 and causing it to finally snap into the left hand notch 32 of the cam 30 when the final retracted position of the parts 95 has been reached. The actuation of the sleeve 22 as just described will also move the stay arm 24 in the same direction and return it into the depression 46 in which condition the arm as well as the head 25 lie entirely within the confines of the sash and 100 out of the plane in which the slot 36 is located. If the locking strips 16 are now moved to an open or inoperative position the sash 10 may be freely swung to any position within its limits of oscillation and 105 may thus for instance be readily and easily cleaned without making it necessary for the cleaner to step outside of the window. By placing the keys 50 only in the possession of authorized persons and by having the 110 parts normally in their outer position so that the plate 35 is normally always in the path of the shank 26 and head 25 the danger of accidental complete pivotal movement of the sash out of the casing and resulting 115 injuries are absolutely prevented and the complete pivotal movement of the sash is possible only after the parts have been adjusted as described by these authorized persons with the aid of the said keys. The counter- 120 acting spring 34 is so arranged that an attempt to move the arm 24 to an inoperative position by exerting a pressure toward the sash therein will be completely counteracted. This is due to the fact that the free 125 end portions of the spring at opposite sides of the projection 33 lie in substantially straight lines between said projection and the corners of the case 18 when the projection is in either notch 32 and thus abso- 130

lutely prevent any movement of the cam excepting with the assistance of the proper key as will be clearly apparent. The attachment is thus positive in its operations and 6 completely safeguarded against tampering by unauthorized persons, it being understood that other more complicated devices may be substituted for the key and key hole construction shown in the illustration to 10 still further guard against such contingencies. The key 49 in the illustrated form may also be used as a means for locking the chains 13 and sash weights 13^b when it is desired to completely remove a sash from the casing. For this purpose the window casing 15 is provided at a suitable point with a recess 15^a adapted to receive the key 49 and end 48 thereof in such a manner that the handle 50 will extend lengthwise of the 15 casing 15 and the forked projection 51 will project at an angle thereto. By simply inserting one of the chains 13 of the sash which is to be removed into the forked projection 51 as shown in Figs. 9, 10 and 11 the 20 said chain will be firmly held and the co-operating weight 13^b thus secured against dropping. The particular sash 10 may now be swung clear of the casing 15 and the pivots 11 detached therefrom to permit the 25 complete removal of said sash, the chains 13 and weight 13^b being meanwhile securely held by the key 50 thus permitting an uninterrupted manipulation of the sash as described. The said pivots 11 are in this manner 30 also maintained in a position in which they may be easily connected with the sash when it is desired to replace the sash in the casing. In the illustrated form of window the key 50 may be connected with either 35 chain 13 for the reason that both chains of each sash are connected with a single weight or with twin weights at one side of the casing. The key may however be similarly used for the purpose described in connection 40 with windows hung and counterbalanced in the ordinary way.

In describing the attachment I have referred to the same in the singular although in practice I prefer to provide duplicate parts at the two opposite vertical sides of the window, it being evident however, that in some cases a single attachment located at one side thereof will be sufficient to secure the intended results. In addition to this it 50 will be readily apparent that the attachment is not limited to use in connection with windows and that the same may readily be combined with other movable elements when a limitation of movement in a certain direction is desired as for instance in doors and the like.

Various changes in the specific form shown and described may be made within the scope of the claims without departing 55 from the spirit of my invention.

I claim:

1. The combination of a stationary support, an element movable relatively thereto, a device attached to said support and means carried by said movable element and movable relatively thereto, said device being in the normal path of said means whereby the latter is arranged to automatically engage said device as said element is moved and arrest the movement thereof. 75

2. The combination of a stationary support, an element movable relatively thereto, a slotted device secured to said support and means pivotally secured to said movable element, said device being in the normal path 80 of said means whereby the latter is arranged to automatically enter said slot as said element is moved to limit the movement thereof.

3. The combination of a relatively stationary frame, a member pivotally mounted thereon, a device secured to said frame, means carried by said member and movable relatively thereto, said device being in the normal path of said means whereby the latter is adapted to automatically engage said device as said member is pivotally moved and arrest said movement and mechanism for moving said means to an inoperative position to permit an unrestricted pivotal 95 movement of said member.

4. The combination of a relatively stationary frame, a member pivotally mounted thereon, a slotted device secured to said frame, an arm pivotally mounted on said member, a projection carried by said arm and arranged to normally travel over a path in which said slotted device is located whereby said projection automatically enters the slot of said device and arrests the pivotal 100 movement of said member and key actuated means for moving said arm to an inoperative position out of the path in which said device is located, whereby an unrestricted pivotal movement of said member 110 is permitted.

5. The combination of a relatively stationary frame, a window sash or the like pivotally mounted thereon, a plate secured to said frame and provided with an open 115 ended slot, a sleeve rotatably and slidably mounted on said window sash or the like, a stay arm carried by said sleeve and movable therewith, a projection on said arm arranged to automatically enter said slot and arrest the pivotal movement of said sash or the like, means for slidably moving said sleeve whereby said arm and projection are moved to and from an operative position and means for locking said sleeve in its adjusted positions. 120

6. The combination of a relatively stationary frame, a window sash or the like pivotally mounted thereon, a plate secured to said frame and provided with an open 130

ended slot, a case carried by said window sash or the like, a bridge pin in said case, a sleeve slidably and rotatably mounted on said bridge pin, a stay arm secured to said sleeve to move therewith, a projection on said arm arranged to automatically enter said slot and swing said arm on said bridge pin whereby the pivotal movement of the sash or the like is arrested, a member rotatably mounted in said case and connected with said sleeve, means for actuating said member to slidably move said sleeve on said bridge pin whereby said arm and projection are moved to and from an operative position and means for locking said member in its adjusted positions.

7. The combination of a relatively stationary frame, a window sash or the like pivotally mounted thereon, a plate secured to said frame and provided with an open ended slot, a resilient clip carried by said plate in registry with said slot, a case carried by said window sash or the like, a bridge pin in said case, a sleeve slidably and rotatably mounted on said bridge pin, a stay arm secured to said sleeve to move therewith, a stem on said arm arranged to automatically enter said slot and swing said arm on said bridge pin whereby the pivotal movement of the sash or the like is arrested, a head on said stem adapted to frictionally engage said resilient clip as said stem moves in said slot, a cam member rotatably mounted in said case and connected with said sleeve, a detachable key actuating said member to slidably move said sleeve on said bridge pin whereby said arm, stem and head are moved to and from an operative position and a counteracting spring for locking said cam-member in its adjusted positions.

8. The combination of a relatively stationary frame, a slidable window sash or the like pivotally mounted thereon, an arm pivotally mounted on said sash, a projection carried by said arm and a plate secured to said frame and provided with an open ended

slot adapted to receive said projection and arrest a pivotal movement of said sash, said slot being formed with a portion adapted to prevent a return movement of said projection out of said slot excepting in a predetermined position of said sash.

9. The combination of a relatively stationary frame, a slidable window sash or the like pivotally mounted thereon, an arm pivotally mounted on said sash, a projection carried by said arm, and a place secured to said frame and provided with an open ended slot adapted to receive said projection and arrest a pivotal movement of said sash, said slot being formed with an angular portion adapted to prevent a return movement of said projection out of said slot excepting in a predetermined position of said sash.

10. The combination of a relatively stationary frame having a recess, a pivoted window sash in said frame, sash chains or the like connected with said sash, counterbalancing means connected with said chains or the like, a device secured to said frame, means carried by said sash and movable relatively thereto, said means being arranged to automatically engage said device as said sash is pivotally moved and arrest said pivotal movement, mechanism for moving said means to an inoperative position to prevent an unrestricted pivotal movement of said sash, a key adapted to actuate said mechanism and arranged to be inserted into the recess of said frame and a forked projection on said key adapted for connection with a sash chain or the like when the key is in said recess whereby a sliding movement of the chain or the like and the counterbalancing means is prevented.

In testimony whereof I have hereunto set my hand in the presence of two subscribing witnesses.

JOHN B. CLERMONT.
